UNITED STATES PATENT OFFICE

ARNOLD H. GOSS, OF DETROIT, MICHIGAN

MECHANICAL REFRIGERATION

Application filed August 28, 1926. Serial No. 132,300.

My invention relates to mechanical refrigeration, and particularly to mechanical refrigeration units of the self-contained type, and the principal object of my invention is to provide a new and improved unit of this type. In the drawings accompanying this specification and forming a part of this application I have shown, for purposes of illustration, one form which my invention may assume.

In these drawings:

Figure 1 is a front elevation of the embodiment of my invention herein shown,

Figure 2 is a view similar to Figure 1 but with the doors open exposing the interior,

Figure 3 is a vertical section taken on the line 3—3 of Figure 4,

Figure 4 is a section on the line 4—4 of Figure 3, while

Figure 5 is a section on the line 5—5 of Figure 3.

The embodiment of my invention herein shown comprises a refrigerator cabinet 11 comprising a front wall 12, a rear wall 13, side walls 14 and 15, a top 16, a horizontal partition 17, and a base 18, the front wall 12, rear wall 11, side walls 14 and 15, top 16, and horizontal partition 17, defining a refrigerating compartment 19, and the front wall 12,

rear wall 13, side walls 14 and 15, horizontal partition 17, and base 18, defining a compressor compartment 20.

Mounted within the refrigerating compartment 19 is a T-partition 21 extending forwardly from the rear wall 13 stopping short of the front wall 12, and dividing the refrigerating compartment 19 into a refrigerating section 22 adapted to receive mechanical refrigeration apparatus, a refrigerated section 23 ar-

ranged to receive material to be refrigerated, and a humidor section 24 arranged to receive a receptacle for the storage of tobacco products, all three sections 22 and 23 and 24 being all open at the front, the humidor section 24 being otherwise completely segregated from the refrigerating and refrigerated sections 22 and 23, and the refrigerating and refrigerated sections 22 and 23 being inter-connected by means of circulation apertures 25 and 26 formed in the T-partition 21.

Mounted within the refrigerating section 22 is mechanical refrigerating apparatus 27 comprising a brine tank 28 containing a suitable expansion coil, not shown, and provided with a plurality of apertures 29 for the reception of trays 30 for the formation of artificial ice under the action of the refrigerating apparatus 27, an expansion valve 31 supported on the brine tank 28 and connected to the inlet end of the expansion coil, end turns 32 supported on the brine tank 28 and connected to the outlet end of the expansion coil and themselves supporting a thermostat 33, a drip pan 34 disposed beneath the brine tank 28 to receive the condensation from the refrigerating apparatus 27, and a drain duct 35 extending from the drip pan 34 through the humidor section 24 into the compressor compartment 20, and thence to any desired point.

Closing the front of the refrigerating section 22 is a shield 36 provided with an aperture 37 affording access to the trays 30.

Mounted within the refrigerated section 23 are a plurality of shelves 38 adapted to support the material to be refrigerated, and themselves supported on brackets 39 and 40 mounted respectively upon the T-partition 21 and the side wall 15.

Mounted within the humidor section 24 is a receptacle 41 supported from the horizontal partition 17 by means of suitable blocks 42, provided at its forward end with an opening 43 affording access to the interior, closing the opening in the forward end of the humidor section 24 to thus completely segregate the space 44 within the humidor section 24 exteriorly of the humidor receptacle 41, and provided with a door 45 tightly closing the opening 43.

Mounted within the compressor compartment 20 is a compressor 46 having its inlet connected by means of a duct 47 to the end turns of the expansion coil within the refrigerating apparatus 27, a condenser 48 having its inlet connected by means of a duct 49 to the outlet of the compressor 46 and its outlet connected by means of a duct 50 to the expansion valve 31, and an electric motor 51 operating the compressor 46 by means of a suitable belt 52 and energized from line wires 53 and 54.

by means of a direct connection to the line wire 54 and a connection to the line wire 53 through the thermostat 33 and an intermediate conductor 55.

5 In the embodiment of my invention herein shown I provide access to the compressor compartment 20 by means of an opening in the front wall 12 arranged to be closed by means of a suitable door 56, and to the refrigerating compartment 19 by means of a single opening 57 affording access at all times to the ice trays 30 and the refrigerated section 23 and the humidor door 45, affording access to the interior of the humidor receptacle 43 by opening the humidor door 45, and affording access to the entire refrigerating apparatus 27 upon removal of the shield 36, and in the embodiment of my invention herein shown I close this opening 57 by 15 means of a single door 58 consisting of an inner wall 59, and an outer wall 60 spaced from the inner wall 59, and carrying between the inner wall 59 and the outer wall 60 a combination lock 61 operable by means of 20 a knob 62 disposed on the exterior face of the door 58 and including a bolt 63 arranged to prevent rotation of a disc 64 carried by a shaft 65 operable by means of a handle 66 and operating bolts 67 and 68 arranged 25 to extend from the top and bottom edges of the door 58 into suitable alining apertures 69 and 70 in the adjacent edges of the front wall 12 of the refrigerator cabinet 11 to secure the door firmly locked in closed position.

30 35 From the above description it will be obvious to those skilled in the art that I have provided mechanical refrigeration means having the expansion means and the control means and the ice means and the refrigerating section and the refrigerated section and the humidor section and the material within the refrigerated section and the material within the humidor section all accessible through a single opening, having a single door for closing this opening, and having on this door a lock disposed within the walls of the door out of communication with the refrigeration compartment and arranged to lock the door closed to thus prevent access to the expansion means and the control means and the refrigerating section and the refrigerated section and the humidor section and the material within the refrigerated section and the material within the humidor section.

40 45 50 55 60 65 70 75 80 85 90 95 100 105 110 115 120 125 130 At the same time it will also be obvious to those skilled in the art that the particular embodiment of my invention herein shown and described may be variously changed and modified without departing from the spirit of my invention or sacrificing the advantages thereof, and it will therefore be understood that the disclosure herein is illustrative only, and that my invention is not limited thereto.

I claim:

16 1. In combination: a refrigerator cabinet

provided with a refrigerating compartment and having a single relatively large opening affording access to said compartment, said compartment being divided into a refrigerated section accessible through said relatively large opening, and a normally sealed heat insulated humidor section separated from said refrigerated section except for a relatively small opening affording access to said humidor section through said relatively large opening; humidor door means tightly closing said relatively small opening; and door means arranged to close said relatively large opening.

2. In combination: a refrigerator cabinet 80 provided with a refrigerating compartment and having a single relatively large opening affording access to said compartment, said compartment being divided into a refrigerating section for the reception of mechanical 85 refrigerating apparatus and accessible through said relatively large opening, a refrigerated section in communication with said refrigerating section and also accessible through said relatively large opening, and a normally sealed humidor section separated from said refrigerating and refrigerated sections by heat insulating means except for a relatively small opening affording access to said humidor section through said relatively 95 large opening; humidor door means provided with heat insulating means tightly closing said relatively small opening; mechanical refrigerating apparatus within said refrigerating section comprising refrigerating means, and means for the formation of artificial ice, under the action of said refrigerating means, accessible through said relatively large opening; and door means arranged to close said relatively large opening.

3. In combination: a refrigerator cabinet provided with a refrigerating compartment and having a single relatively large opening affording access to said compartment, said compartment being divided into a refrigerating section for the reception of mechanical refrigerating apparatus and accessible through said relatively large opening, a refrigerated section in communication with said refrigerating section and also accessible through said relatively large opening, and a humidor section separated and heat insulated from said refrigerating and refrigerated sections except for a relatively small opening affording access to said humidor section through said relatively large opening; heat insulating humidor door means tightly closing said relatively small opening; mechanical refrigerating apparatus within said refrigerating section comprising refrigerating means, and means for the formation of artificial ice, under the action of said refrigerating means, accessible through said relatively large opening; a shield closing off said mechanical refrigerating apparatus

from said relatively large opening except for a second relatively small opening affording access to said ice means; and door means arranged to close said relatively large opening.

5 In testimony whereof I hereunto affix my signature.

ARNOLD H. GOSS.
